UNITED STATES PATENT OFFICE.

GEORGE S. BARKENTIN, OF NEW BRITAIN, CONNECTICUT, ASSIGNOR TO
P. & F. CORBIN, OF SAME PLACE.

DESIGN FOR A LATCH-CASE.

SPECIFICATION forming part of Design No. 19,553, dated January 7, 1890.

Application filed October 30, 1889. Serial No. 328,708. Term of patent 7 years.

To all whom it may concern:

Be it known that I, GEORGE S. BARKENTIN, a citizen of the United States, residing at New Britain, in the county of Hartford and State of Connecticut, have invented and produced a new and original Design for a Latch-Case, of which the following is a specification, reference being had to the accompanying drawings, forming part thereof.

10 Figure 1 is a front elevation of the latch-case, showing my design; and Fig. 2 is a plan view of the same.

15 The leading feature of my design consists in the vertically-arranged ornamental beads on the sides and the chain-like ornaments at the top and bottom, figured in imitation of cords.

20 A A are the sides of my latch-case, and B the top, which is like the bottom. At the back edge of the case is a vertical bead 3, and at the front edge a double bead 4. Parallel to said double bead, at some little distance therefrom, is another plain bead 5. Between the double bead 4 and said plain bead 5 is an 25 ornamental bead 6, formed of curved and straight edges in strap-like form, as shown, and on that side of the bead 5 which faces the back edge of the case is a vertical bead 7,

figured in imitation of a cord, and provided at intervals with leaf-like projecting ornaments 8. The top and bottom are also ornamented with a cord-like bead arranged in the form of three chain-links 9 9 9, as shown.

What I claim is—

1. The design for a latch-case herein shown 35 and described, the same comprising the sides A A, having the plain vertical beads, the strap-like and cord-like ornamental beads, and the top and bottom having the cord-like bead arranged in the form of three chain-links, as set forth.

2. In the design for a latch-case herein shown and described, the side A, having the plain beads 3 4 5, the ornamental strap-like beads 6, and the vertical cord-like beads 7 8, 45 as set forth.

3. In the design for a latch-case herein shown and described, the top plate having the bead arranged in the form of three chain-links and figured in imitation of a cord, as 50 set forth.

GEORGE S. BARKENTIN.
